 11 Claims. (Cl. 103—51)

The present invention relates to a fluid moving machine, and more particularly to a double acting plunger pump and hydraulic motor combination with a pair of pump chambers.

For hydrodynamic cleaning operations, particularly for the cleaning of sewers and for mines, water pumps are required which combine a very low weight with easy adjustability of the pumped amount and of the water pressure. Due to the fact that very great energy amounts are involved, great efficiency of the pumps is required. Furthermore, the pumps serving these purposes should require very little service.

Pressure water pumps of high efficiency are known. Three plunger pumps are widely used, particularly for the supply of water to boilers. Multistage rotary pumps operate at lower efficiency, but serve the purpose. Both pump types are adjustable to a certain extent, but when the pump is adjusted to a different output, the efficiency is reduced.

Piston pumps require very heavy crank drives with cross heads, and the comparatively low rotary speed of this type of pumps necessitates the use of reduction gears, and the great torques involved require very heavy constructions.

When high pressure pumps are improperly controlled, the pumping pressure is exerted against closed valves. In order to avoid very serious damage to the pumps under such circumstances, substantial expenditures are required. The heat created by friction at the sealing means of the plunger may cause the destruction, or substantial damage to the sealing means, and when the plungers or cylinders are chrome plated, the chromium layer may peel off.

It is one object of the invention to overcome the disadvantages of known pump constructions, and to provide a fluid moving machine which operates at high efficiency at high loads and pressures.

Another object of the invention is to provide a fluid moving machine constructed of simple parts and having a low weight per unit of pump fluid and pressure.

Another object of the invention is to provide a fluid moving machine operable free of vibrations in all positions.

With these objects in view, the present invention relates to a fluid moving machine in which plunger means are operated by a driving fluid to pump another fluid.

One embodiment of the invention includes a double plunger pump with a pair of pump chambers, and having a double plunger in the form of cylindrical piston means and slidably guided on a stationary part for reciprocating movement during which a valve controlling the supply and discharge of a driving fluid to the interior of the plunger is operated.

A preferred embodiment of the invention comprises housing means formed with an inner cavity for a pumped fluid, and including a partition means dividing the cavity into two rooms which have first inlet and outlet means; plunger means including a pair of pistons located on opposite sides of the partition means and a tubular member connecting the pistons and being guided in the partition means; second inlet and outlet means for driving fluid which preferably passes through a conduit in a tubular support which extends through the partition means and passes through the pistons; and valve means for connect-

2

ing the second inlet and outlet means with the motor chambers.

The plunger means define in each room of the housing means a pump chamber communicating with first inlet and outlet means, and the pistons and tubular member defining with the partition means a pair of motor chambers located on opposite sides of the partition means.

The valve means are movable between first and second positions for supplying the driving fluid to the first motor chamber while discharging the same from the same motor chamber, and for supplying the driving fluid to the second motor chamber while discharging the same from the first motor chamber. This causes reciprocation of the plunger means since the driving fluid exerts pressure on the pistons, and the reciprocating plunger means, and more particularly the pistons, engage a control means which causes shifting of the valve means so that the reciprocation of the plunger is automatically continued.

The valve means are mounted in the partition means communicating with the conduit of the tubular support so that driving fluid supplied to, or discharged from the conduit passes through the valve means into the motor chambers.

The valve means comprise preferably a main valve which distributes the driving fluid, and a valve control member which is shifted by the moving plunger means and hydraulically controls the main valve which has a piston portion moving in a control chamber to which pressure fluid is admitted under the control of the valve control member.

The valve control member is mounted in the partition means and has end portions projecting into the motor chambers so as to be engaged by the inner surfaces of the pistons during the reciprocating movement of the plunger means.

In one embodiment of the invention, the main valve is turnable in the partition means, and in another embodiment of the invention the main valve is mounted in the partition means for translatory movement. The turnable main valve is preferably controlled by a pair of valve control members which, when shifted by the reciprocating plunger means, open and close ducts in the partitioning means for supplying pressure fluid to the control chamber in which the piston portion of the main valve is located.

During each reciprocating stroke of the plunger, the main valve is hydraulically locked, and cannot turn to a position reversing the flow of the driving fluid to the motor chambers until the valve control member is actuated by the reciprocating plunger means at the end of a reciprocating stroke.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a longitudinal sectional view of a fluid moving machine according to one embodiment of the invention provided with a turnable main valve;

FIG. 2 is a fragmentary longitudinal sectional view illustrating the center portion of FIG. 1 on a larger scale, the section being taken on line II—II in FIG. 3;

FIG. 3 is a cross-sectional view taken on line III—III in FIG. 2;

FIG. 4 is a cross-sectional view taken on line IV—IV in FIG. 2;

FIG. 5 is a fragmentary longitudinal sectional view illustrating the center portion of another embodiment of the invention in which the main valve is shiftable in a

translatory movement, the section being taken on line V—V in FIG. 6;

FIG. 6 is a longitudinal sectional view taken on line VI—VI in FIG. 5; and

FIG. 7 is a cross-sectional view taken on line VII—VII in FIG. 5.

Referring now to the drawings, and more particularly to FIGS. 1 and 2, a housing has two head portions 1 and 2 with inlet conduit means 3 through which a fluid to be pumped is supplied. Check valve means 50 and 51 cover inlets 3b in walls 3a, and open when the corresponding pump chambers 5 and 6 are expanded and suction is applied to valves 50 and 51. A pair of cylindrical housing portions 1a and 2a connect the heads 1 and 2 and form outlets communicating with pump chambers 5 and 6 and closed by valves 52 and 53 from which pumped fluid is discharged when the corresponding pump chambers 5 and 6 are reduced in volume.

The outlets 1b and 2b are connected by a tube 4 into which pressure fluid is pumped. A tie rod 4a connects the outlet means 1b and 2b.

A pair of aligned tubular supports 12 and 13 are respectively mounted in the heads 1 and 2 and secured to the same by nuts 17 and 18 which engage threaded portions of tubular supports 12 and 13. The inner ends of the tubular supports 12 and 13 are threaded at 9a, see FIG. 2, to sleeve portions 9b of a partition means 9. An annular member 7 surrounds the adjacent ends of the tubular members 1a and 2a and has inner sealing means 7a of annular configuration which form a circular gap with annular sealing means 7b which are secured to partitioning means 9. A tubular member 8 is mounted in this gap for sliding movement and is divided by partitioning means 9. Pistons 10 and 11 are secured to the ends of tubular member 8 and surround the tubular supports 12 and 13. Sealing rings 14 are provided between the tubular supports and the pistons 10 and 11.

The partition means 9, and pistons 10 and 11 form in the tubular member 8 a pair of motor chambers 26 and 28. Pump chambers 5 and 6 are formed in the pump housing between the heads 1 and 2 and pistons 10 and 11. Tubular supports 12 and 13 have inner conduits 15 and 16 for a driving fluid which is supplied to the inlet of conduit 15 at the end of tubular support 13, and which is discharged from the outlet of conduit 16 at the end of tubular support 13.

The inner ends of tubular supports 12 and 13 have inner cylindrical surfaces 13a and 13b in which a main valve 19 is mounted for turning movement. The end portions of main valve 19 abut roller bearing means 20 and 21 so that the main valve 19 cannot be axially displaced.

As best seen in FIG. 2, main valve 19 has valve channels 24 and 30 which open at the ends of valve 19 into conduits 15 and 16. Valve channel 30 has two ports 47 and 47a, and valve channel 24 has two ports 46 and 46a. In the illustrated position of valve 19, port 47a communicates with an opening 29 in tubular support 13 which leads to the motor chamber 28 within the plunger 8, 10, 11. Port 46a communicates with an opening 25 which leads to the motor chamber 26. In the illustrated position of main valve 19, ports 47 and 46 are closed, but when main valve 19 is turned, ports 46 and 47 respectively communicate with openings 29 and 25 in tubular supports 13 and 12, respectively, so that driving fluid entering channel 24 from conduit 15 passes into motor chamber 28, while the driving liquid is discharged from motor chamber 26 and channel 30 into the conduit 16 for reversing the stroke of plunger 8, 10, 11.

To effect turning of the main valve through 90°, the main valve is provided with a segment-shaped piston portion 35 best seen in FIG. 3. Piston portion 35 has a shorter axial length than the main valve, and is located in a corresponding control chamber 34 which extends

through an angle of 270° to the end faces of a segment-shaped stationary member 36 which is secured to the main part of the partition means 9 by a screw 45a.

In the position of control valve 19 shown in FIGS. 5 and 3, pressure fluid has entered the control chamber 34 through a duct 31 and has urged control piston portion 35 to the position abutting one end face of stop 36. When pressure fluid is supplied through duct 42, piston portion 35 is urged away from member 36 and turns the control valve through 180° while the control chamber 45 expands. The turning of the valve is terminated when piston portion 35 abuts the other end of member 36.

The supply of pressure fluid to valve control chamber 34, 45 is controlled by valve control members 22 and 23 which are mounted for sliding movement in axial direction in corresponding bores of partition means 9. The ends of control members 22, 23 are connected by arcuate links 39 and 38 best seen in FIG. 4. In the position shown in FIG. 2, link 39 abuts an end face of partition means 9 so that valve control members 22, 23 cannot move farther to the right as viewed in FIG. 2.

Valve control members 22, 23 were placed in this position by piston 11 moving to the right as viewed in FIG. 1, and when the plunger moves in the opposite direction, piston 10 engages with its inner surface the other ends of valve control members 22, 23 and pushes the same to the left until link 38 abuts a surface of partition means 9.

Control valve member 23 has a thinner central portion forming an annular room 32 which communicates with duct 31. Valve control member 22 has two thinner portions surrounded by annular rooms 44 and 44a. In the illustrated position, annular room 44a communicates with duct 42. In the shifted position of valve control member 22, annular room 44 communicates with duct 35.

Main valve 19 has two bores 33 and 41 respectively communicating with channels 24 and 30. Annular channels 43 and 40 are provided in tubular supports 13 and 12, respectively and cooperate with bores 33 and 41. Four bores 39a are provided in partition means 9 for connecting the annular channels 40 and 43 with the annular rooms 32, 44, 44a.

Drive fluid enters through the inlet at the right end of tubular support 13 into conduit 15 and flows in the illustrated position of main valve 19 into valve channel 24, through port 46a, and opening 25 into motor chamber 26 to act on piston 11 whereby the plunger moves to the left as viewed in FIG. 1 and reduces the size of pump chamber 6 so that the fluid to be pumped is discharged through outlet valve 43 and outlet means 1b, and also outlet means 2b which is connected with outlet means 1b by the conduit 4. Valve 50 closes due to the pressure in pump chamber 6.

The movement of the plunger to the left in the direction of the arrow 27 causes piston 10 to reduce the volume of motor chamber 28 so that the driving fluid therein flows through opening 29, port 47a and valve channel 30 into the discharge conduit 16 in tubular support 12 and out of the outlet at the left end of tubular support 12 as viewed in FIG. 1.

During movement of plunger 8, 11, 10 to the left, pump chamber 5 expands, and fluid to be pumped is sucked through inlet 3 and valve 51 into pump chamber 5 while valve 52 closes.

During this reciprocating stroke of the plunger 8, 10, 11, main valve 19 is locked in the illustrated position, since the pressure fluid in conduit 15 passes through bore 33, annular channel 43, bore 39, annular room 32 and bore 31 into valve control chamber 34, see also FIG. 3, so that piston portion 35 is held by the pressure in control chamber 34 in the illustrated position so that the main valve establishes the necessary fluid connections for the reciprocating stroke of the plunger to the left.

When the inner surface of piston 10 engages the ends 75 of valve control members 22 and 23, the same are

pushed to the left as viewed in FIGS. 1 and 2 until link 38 abuts an end face of partition means 9. In this position of valve control members 22, 23, bore 42 communicates with annular room 44 of valve control member 22, and bore 33 is separated from annular room 32 of valve control member 23 and thereby from bore 31 and valve control chamber 34.

Pressure fluid is discharged from control chamber 34 through bore 31, annular room 32, bore 39a in sleeve 39b, annular channel 40, and bore 41 into valve channel 30 which communicates through conduit 16 with the outlet for the driving fluid.

At the same time, pressure fluid enters from conduit 15 through valve channel 24, bore 33, annular channel 43, bore 39c, annular room 44 and bore 42 into control chamber 45 to urge piston portion 35 to move in clockwise direction through 180° until abutting the other end face of stationary member 36. Valve 19 turns with the piston portion through 180° so that in the new position of the valve, pressure fluid enters from conduit 15 into valve channel 34 and passes through port 45 and opening 29 into motor chamber 28 to drive piston 10 to the right as viewed in FIG. 1 whereby the volume of pump chamber 5 is reduced and fluid to be pumped is discharged through valve 52 and outlet means 2b, 4 and 1b.

At the same time, drive fluid discharged from motor chamber 26 passes through opening 25 and port 47 into valve channel 30 and from there into discharge conduit 16.

This stroke of the plunger means 8, 10, 11 is continued until the inner surface 49 of piston 11 engages control members 22 and 23 and shifts the same to the right to place the same in the condition shown in FIG. 2 which causes a corresponding turning of the main valve 19 in counterclockwise direction to the position shown in FIGS. 2 and 3.

In the modified embodiment illustrated in FIGS. 5 and 6, the main valve is not turned but shifted in a translatory movement by a valve control member operated by the pistons of the plunger. The general arrangement of the pump component is the same as shown in FIG. 1, and the plunger means 50 has two pistons 67 and 82 guided on tubular supports 12' and 13' and a tubular portion 8' which slides on a partition means 9'. A ring-shaped member with inner sealing means, corresponding to members 7, 7a described with reference to FIG. 2, surrounds the tubular portion 8' of plunger means 50, but is not shown in FIGS. 5 and 6. The inner ends of tubular supports 12' and 13' are secured to partition means 9', and form an inner cylindrical chamber in which the main valve 54 is mounted for limited axial movement between two end positions. Partitioning means 8' has an axial bore in which a valve control member 69 is mounted for axial movement between two control positions determined, respectively by abutment of the heads 68 and 83 on end faces of partition means 9', as shown in FIG. 6. Drive fluid under pressure is supplied through conduit 53a and flows into valve chamber 55, through chamber portion 56, bore 57 and conduit 58 into motor chamber 59 to move plunger means 8' to the left in the direction of the arrow 60 in FIG. 5. At the same time, the contracting motor chamber 61 discharges drive fluid through conduit 62, bore 63, and valve channel 64 into the discharge conduit 65 of the tubular support 13'.

During movement of the plunger means 8' in the direction of the arrow 60 in FIG. 5, pump chamber 6 is reduced in volume, and pump chamber 5 is increased in volume so that fluid is pumped out of outlet 1b, and sucked into inlet 3 as described with reference to FIG. 1.

At the end of the reciprocating stroke to the left, the inner surface of piston 67 engages the head 68 of valve control member 69 and shifts the same to its other position in which head 68 abuts partition means 9'.

Valve control member 69 has a thinner central portion surrounded by an annular room 72 in partition means 9'. A bore 73 in tubular support 13' connects annular room 72 with an annular control chamber 70 provided between a portion of the main valve 54 and a corresponding face of tubular support 13'. On the other side of main valve 54, a corresponding annular control chamber 74 is provided. Main valve 54 has a slot 87 into which the end portion 86 of the stop screw 85 projects to limit translatory movement of main valve 54 into end positions, one of which is illustrated in FIGS. 5 and 6.

When the plunger means 8' has shifted valve control member 69 to the left, a bore 71 in tubular support 12' and partition means 9' communicates with annular room 72 so that pressure fluid flows from conduit 53a, bore 71, annular room 72, and bore 73 into the annular control chamber 70 to move main valve 54 to the left to its other end position. The other control chamber 74 discharges fluid through bores 75, 76, FIG. 5, in the body of main body 54 into valve channel 64 which communicates with the discharge conduit 65 in tubular support 13'.

In the second position of main valve 54, valve channel 64 registers with a bore 77 communicating with a conduit 58a which opens into motor chamber 59 so that the same is connected to the discharge conduit 65 in tubular support 13'.

Drive fluid under pressure flows through valve channel 55, 56, a bore 78, and a conduit 79 into motor chamber 61 to urge plunger means 8' to the right. Conduit 79 and bore 78 are circumferentially spaced from conduit 58 and bore 57, and valve channel 55 has a wider portion 56 covering in circumferential direction the two bores 57 and 78.

While plunger means 8' moves to the right, the volume of pump chamber 5 is reduced, and fluid is discharged through outlet 2b. The volume of pump chamber 6 increases, and fluid is sucked into inlet 3 and passes through valve 50, as described with reference to FIG. 1.

When plunger means 8' has reached a position in which its inner surface 81 engages the head 83 of valve control member 69, the same is shifted to the position illustrated in FIG. 6. In this position, valve control chamber 70 is connected by bore 73, annular room 72, and bore 84 with discharge conduit 65 in tubular support 13'. The pressure of the drive fluid entering into valve channel 55 from conduit 53a is sufficient to urge main valve 54 to the right hand end position when control chamber 70 is relieved of pressure.

In both embodiments of the invention, the pump housing 1, 1a, 2 has an inner cavity which is divided by the partition means 9, 9' into two rooms. The plunger means 8, 10, 11 forms pump chambers 5 and 6 in their respective rooms, and motor chambers 26, 28 in the interior of the plunger. The tubular member 8 is sealed from the pump chambers only in the region of the partition means 9, 9' so that thin annular portions of pump chambers extend between housing portion 1a and tubular member 8, 8' to the partition. No sealing means are required between pistons 10, 11 and the tubular housing portion 1a.

It will be understood that each of the elements described above, or two or more together, may also find a useful application in other types of fluid moving machines differing from the types described above.

While the invention has been illustrated and described as embodied in a motor pump combination comprising a plunger having inner motor chambers separated by a partition in which valve means are provided for alternately connecting the motor chambers to a driving fluid, it is not intended to be limited to the details shown, since various modifications and structural changes may be made without departing in any way from the spirit of the present invention.

Without further analysis, the foregoing will so fully reveal the gist of the present invention that others can

by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A fluid moving machine comprising, in combination, housing means formed with an inner cavity for a pumped fluid, and including a partition means dividing said cavity into two rooms, each room having first inlet and first outlet means; plunger means including a pair of pistons located on opposite sides of said partition means in said rooms, and a tubular member connecting said pistons having an axis and being guided in said partition means, said plunger means defining in each room a pump chamber communicating with said first inlet and outlet means, and said pistons and tubular member defining with said partition means a pair of motor chambers located on opposite sides of said partition means; second inlet and outlet means for a driving fluid; and valve means mounted in said partition means for connecting said second inlet and outlet means and with said motor chambers, said valve means being formed with first and second conduits and being located centered in said axis, said valve means having first and second positions for supplying said driving fluid through said first conduit to said first motor chamber while discharging the same from said second motor chamber through said second conduit, and for supplying said driving fluid to said second motor chamber through said second conduit while discharging the same from said first motor chamber through said first conduit, whereby said plunger means are reciprocated, said first and second valve conduits being arranged and constructed so that the fluid pressure therein holds said valve member centered in said axis, said valve means including control means operated by said reciprocating plunger means to move said valve means alternately to said first and second positions.

2. A machine according to claim 1, wherein said control means include two control members having ends projecting in axial direction from said partition means, arcuate links connecting said ends and extending about said valve means, and a piston in a chamber in said partition means connected with said valve means, said control members controlling the flow of fluid in said chamber for turning said valve means.

3. A machine according to claim 1, and including anti-friction bearings supporting the ends of said valve means in said partition means.

4. A machine according to claim 1, wherein said valve means includes a stepped axially movable piston having a surface subjected to fluid pressure, and a control chamber means in said partition means receiving said piston and having an hydraulically effective annular surface having a greater area than said surface of said piston, said control chamber being hydraulically connected by said control means with said second inlet and outlet means, respectively.

5. A machine according to claim 4, wherein said piston has a circular surface in said second inlet means subjected to fluid pressure, and wherein said annular surface has an area substantially twice the area of said circular surface; and wherein said valve means closes a chamber connected by a bore in said partition means with said second outlet means.

6. A fluid moving machine comprising, in combination, housing means formed with an inner cavity having first inlet and outlet means, and including a partition means dividing said cavity; tubular support means supported on said housing means and on said partition means and located in said cavity; cylindrical plunger means located in said cavity and mounted on said partition means and said tubular support means for reciprocating movement, said plunger means defining in said cavity a pair of pump chambers, and defining in the interior thereof with said partition means a pair of motor chambers; and valve means mounted in said partition means for turning movement between two positions for connecting one or the other of said motor chambers to the interior of said tubular support means so that a driving fluid supplied through the same causes reciprocation of said plunger means; and a valve control member mounted on said partition means and operated by said reciprocating plunger means to shift said valve means between said

means and said tubular support means for reciprocating movement, said plunger means defining in said cavity a pair of pump chambers, and defining in the interior thereof with said partition means a pair of motor chambers; valve means mounted in said partition means for turning movement between two positions for connecting one or the other of said motor chambers to the interior of said tubular support means so that a driving fluid supplied through the same causes reciprocation of said plunger means; a valve control member mounted on said partition means and operated by said reciprocating plunger means to shift said valve means between said positions, said valve control member being hydraulically connected with said valve means for shifting the latter between said two positions when said valve control member is shifted by said reciprocating plunger means.

7. A fluid moving machine comprising, in combination, housing means formed with an inner cavity for a pumped fluid, and including a partition means dividing said cavity into two rooms, each room having first inlet and first outlet means; plunger means including a pair of pistons located on opposite sides of said partition means in said rooms, and a tubular member connecting said pistons and being guided in said partition means, said plunger means defining in each room a pump chamber communicating with said first inlet and outlet means, and said pistons and tubular member defining with said partition means a pair of motor chambers located on opposite sides of said partition means; a tubular support having an axis secured to said housing means extending through said partition means and said pump chambers and motor chambers and passing through said pistons movably supporting the same, said tubular support being formed with an inner conduit having a second inlet means at one end of said tubular support and a second outlet means at the other end of said tubular support for admitting and discharging a driving fluid; and valve means mounted in said partition means communicating with said conduit and said second inlet and outlet means on one hand, and with said motor chambers on the other hand, said valve means being formed with first and second conduits and being located centered in said axis, said valve means having first and second positions for supplying said driving fluid through said first conduit to said first motor chamber while discharging the same from said second motor chamber through said second conduit, and for supplying said driving fluid to said second motor chamber through said second conduit while discharging the same from said first motor chamber through said first conduit, whereby said plunger means are reciprocated, said first and second valve conduits being arranged and constructed so that the fluid pressure therein holds said valve member centered in said axis, said valve means including control means operated by said reciprocating plunger means to move said valve means alternately to said first and second positions.

8. A fluid moving machine comprising, in combination, housing means formed with an inner cavity having first inlet and outlet means, and including a partition means dividing said cavity; tubular support means supported on said housing means and on said partition means and located in said cavity; cylindrical plunger means located in said cavity and mounted on said partition means and said tubular support means for reciprocating movement, said plunger means defining in said cavity a pair of pump chambers, and defining in the interior thereof with said partition means a pair of motor chambers; and valve means mounted in said partition means for turning movement between two positions for connecting one or the other of said motor chambers to the interior of said tubular support means so that a driving fluid supplied through the same causes reciprocation of said plunger means; and a valve control member mounted on said partition means and operated by said reciprocating plunger means to shift said valve means between said

positions, said valve control means including two valve control members mounted for translatory movement on said partition means, and being interconnected with each other for simultaneous movement, said valve control members being hydraulically connected with said valve means for shifting the latter between said two positions when said valve control members are shifted by said reciprocating plunger means.

9. A machine as set forth in claim 8 wherein said main valve has valve channels communicating with the interior of said tubular support means to receive a driving fluid from the same, and wherein said partition means is formed with ducts controlled by said valve control means for connecting said valve channels with said motor chambers.

10. A fluid moving machine comprising, in combination, housing means formed with an inner cavity having first inlet and outlet means, and including a partition means dividing said cavity; tubular support means supported on said housing means and on said partition means and located in said cavity; cylindrical plunger means located in said cavity and mounted on said partition means and said tubular support means for reciprocating movement, said plunger means defining in said cavity a pair of pump chambers, and defining in the interior thereof with said partition means a pair of motor chambers; valve means mounted in said partition means and having two positions for connecting one or the other of said motor chambers to the interior of said tubular support means so that a driving fluid supplied through the same causes reciprocation of said plunger means; and a valve control member mounted on said partition means and operated by said reciprocating plunger means to shift said valve means between said positions; first sealing means on the periphery of said partitioning means in sliding engagement with the inner surface of said cylinder

5 drical plunger means; and a ring mounted on said housing means and surrounding said cylindrical plunger means in the region of said partition means and having second sealing means in engagement with the outer surface of said cylindrical plunger means.

11. A fluid moving machine comprising, in combination, housing means formed with an inner cavity having first inlet and outlet means, and including a partition means dividing said cavity; tubular support means supported on said housing means and on said partition means and located in said cavity; cylindrical plunger means located in said cavity and mounted on said partition means and said tubular support means for reciprocating movement, said plunger means defining in said cavity a pair of pump chambers, and defining in the interior thereof with said partition means a pair of motor chambers; valve means mounted in said partition means for turning movement between two positions for connecting one or the other of said motor chambers to the interior of said tubular support means so that a driving fluid supplied through the same causes reciprocation of said plunger means; a valve control member mounted on said partition means and operated by said reciprocating plunger means to shift said valve means between said positions; and antifriction bearing means at the end of said valve means supporting the same against axial movement.
